(57) **CLAIM**

The ornamental design for a notebook computer, as shown and described.

DESCRIPTION

FIG. 1 is a perspective view of a notebook computer showing my new design;

FIG. 2 is another perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof;

FIG. 9 is a perspective view thereof, shown in a state of use;

FIG. 10 is an enlarged view of portion '10' in FIG. 1;

FIG. 11 is an enlarged view of portion '11' in FIG. 2;

FIG. 12 is an enlarged view of portion '12' in FIG. 9; and,

FIG. 13 is an enlarged view of portion '13' in FIG. 9.

The dashed broken lines illustrate portions of the article that form no part of the claimed design. The dot-dash broken lines represent the boundaries of the claimed design, and form no part thereof. The dot-dot-dash broken lines surrounding detail views are for annotation purposes only and form no part thereof.

1 Claim, 11 Drawing Sheets
